P. HASTINGS.

Plow.

Patented Dec. 19, 1833.

UNITED STATES PATENT OFFICE.

PETER HASTINGS, OF DAGSBOROUGH, DELAWARE.

IMPROVEMENT IN PLOWS.

Specification forming part of Letters Patent dated December 19, 1833.

To all whom it may concern:

Be it known that I, PETER HASTINGS, of Dagsborough, county of Sussex, and State of Delaware, have made an Improvement on Barnard's Patented Plow, which is described as follows:

Mr. Barnard, in the plow which he has patented, makes a movable share of about four inches in height in front, which he attaches to a cast-iron mold-board and landside by bolts and screws, but is not of sufficient height to protect the mold-board in deep, or, indeed, in ordinary plowing.

The improvement which I have made on Mr. Barnard's plow, and which I wish to secure by Letters Patent, consists in casting the movable share and landside sufficiently deep to protect the front of the mold-board from most of

the wear to which it is exposed by his plan. To effect this object, a recess is cast in the mold-board sufficiently large and deep to receive my improved share and landside. The share is then attached to the mold-board by bolts and screws placed in proper places for that purpose. The cutting of the sward, &c., is therefore performed wholly by the cutting-edge of the share, and not by any part of the mold-board, whereby a considerable saving of expense for mold-boards is accomplished, because when one share is worn out it can easily be replaced by another at a trifling expense.

PETER HASTINGS.
